HAT

Filed March 24, 1925

UNITED STATES PATENT OFFICE.

GERALD H. SIMON, OF SAN FRANCISCO, CALIFORNIA.

HAT.

Application filed March 24, 1925. Serial No. 17,955.

This invention relates to the art of millinery and particularly to hats and the method of manufacturing same.

My invention is particularly directed to what are called sport hats for ladies and misses, and an object of the invention is to provide a hat which, while possessing a neat, snappy and dressy appearance, shall be characterized by means inherently possessed of form, strength and durability lending qualities that normally function to hold the hat in shape, and which will permit the hat to be flexed, crumpled, folded or crushed, and its walls brought together whereby it can be arranged in a compact package to satisfy the convenience and desires of the user or permit the hat to be arranged for shipment or storage.

A decidedly important feature of the invention is to provide a hat characterized by means which injects into the finished article a highly desirable, ornamental and attractive pattern, and means whereby the head size of the hat and depth of the crown can be changed instantly to suit varying requirements, and further, the provision of means which gives form retaining quality to the brim.

A still further object of the invention is to provide a hat constructed from a strip of material of suitable width formed of a plurality of braided or plaited strands, the colors of which can be gaged or calculated so that unlimited numbers of patterns can, on determined calculation, be grafted into the finished article, the said strip being spirally arranged with its wound portions edge to edge and connected together in a manner that will make it appear to the eye that the hat is a solid one piece woven structure.

With the above and other objects in view which will appear as the nature of the invention is better understood, the same consists in the improved construction and novel arrangement of parts which will hereinafter be fully described and particularly pointed out in the claim.

In the accompanying drawings has been illustrated a single and preferred form of the invention, it being, however, understood that no limitations are necessarily made to the precise structural details therein exhibited, but that changes, alterations and modifications within the scope of the claim may be resorted to when desired.

Figure 1 is a perspective view of the hat;

Figure 2 is a plan view of a portion of the braid from which the hat is formed;

Figure 3 is a plan view of what I have called the foundation parts of the braid before same are interwoven with the other parts;

Figure 4 is a plan view of portions of two spirals of the braid showing the edge-to-edge weave thereof; and

Figure 5 is a diagrammatic illustration showing the manner of taking up and regulating the depth of the crown.

In carrying the invention into practice, I do not wish to be limited to the number of parts which go into the manufacture of the braid, but I preferably use five strips or strands of material, two of said strands, for instance A and B, being in the form of ribbon of suitable width folded zigzag to provide alternate leads C extending in one direction, and connecting leads D extending in an opposite direction. These strands A and B when folded zigzag, as above set forth are placed one on top of the other or superimposed relatively as shown in Figure 3.

These strands may be of uniform color, or, for the purpose of varying the ornamental effect and pattern which they inject or graft into the finished hat, same may be of respectively different colors. Variegated ribbons may also be employed to further multiply the color producing effect.

Interlaced or woven relatively and with the strands A and B are narrow strands 1, 2 and 3. These five strands are formed by plaiting or weaving same together either by hand or machine, the latter being preferred in the commercial manufacture of hats in large quantities.

The aforesaid five parts, A, B, 1, 2 and 3 produce a braid-like element of single length form. These parts may be of suitable grade and texture, and in practice I can use silk, felt, cotton, wool or other materials, electing those of the textile variety so that the manufactured hat will be of the rough and ready type, so to speak, wherein the finished structure can be collapsed, knocked down, folded, rolled or crushed, without disastrous results.

In other words, the combination of parts herein set forth gives to the finished article a very durable quality, one of excellent body which will hold its form when set up for use, and even though the hat may be rolled,

crushed or folded for storage or otherwise, this does not destroy or in any way hurt the article from a standpoint of extreme durability, form retaining qualities and artistic 5 and dressy appearance.

The strands 1, 2 and 3 may be of the same color, or like the strands A and B, same can be of relatively different colors. In this respect, the combination of colors can be 10 again varied at the discretion or choice of the maker, so that an exceedingly large range of color and pattern schemes can be carried out and satisfactorily produced with minute exactness.

15 In the process of weaving the parts A, B and 1, 2 and 3, I employ a comparatively loose weave so that said parts stand out prominently and appear somewhat fluffy or tufted-like in the made-up hat. When A 20 is of one color and B another, the finished hat will be characterized by uniform squares of green separated by sections of gray, for example. The strands 1, 2 and 3 can be of harmonizing colors so as to produce a hat 25 of highly artistic merit. Hats of solid color can be varied by regulating the introduction of colored strands in the manufacture of the braid.

I can again increase the number of pattern 30 producing effects by taking a section of braid following one color scheme and joining it to a braid of another color scheme so that, for instance, the brim of the hat may be different from the crown, or vice versa, 35 or parts of either the crown or brim made with variation as to color scheme and design.

After having produced a braid of uniform width, I take a hat block or suitable 40 form, and, for example, temporarily tack the front end of the braid to the base of the form. I then wind the braid spirally about the form so that the wound portions come edge to edge. In progression with this 45 method of spirally winding the braid about the form, I weave a braid 4 (as shown in Figure 4) through the folds of the meeting edges of said wound portions. This method is carried on continuously until the end of the hat is reached, and I may start from the 50 brim and end at the top of the crown, or vice versa. This method may be reversed, as it is just as easy to start from the crown and go down to the end of the brim, and in this respect I do not wish to be limited. In 55 this manner of securing the edges together, it is difficult to detect a line of demarcation

and, to the eye, the hat has the appearance of a solid woven structure.

A hat constructed in accordance with the foregoing is what is commercially known as 60 the sport type, and it needs no trimmings, but if desired, a ribbon may be passed around the crown near the brim and woven through parts of the braid and its ends tied in a bow, as clearly shown in Figure 1. By 65 using this ribbon I am also able to regulate the head size of the hat.

While I have described that I preferably use textile material, such as ribbon of silk, 70 cotton, wool, or felt or the like, all of suitable shades and texture, it shall be understood that modifications within the scope of the hereto annexed claim can be made. I purposely have selected the above named 75 materials because a hat of great strength, durability and artistic refinement of the crush or knock-down type can be produced. In cases where this feature is not desired, the materials of which the braid is formed 80 can be varied.

The strands 1, 2 and 3 are preferably of 85 tougher and stiffer texture than the strands A and B so as to give stiffness to the finished hat to the extent that the form of the hat is retained without use of a supporting frame.

Interwoven in the folds of the edge of the 90 brim of the hat is a tape 5 which serves to hold the brim in form. It gives certain body to the brim and yet permits same to be readily flexed as desired.

If one wishes to change the depth of the 95 hat, a tuck 6 can be made on the right side of the crown as shown in Figure 5 and secured by stitching 7.

I claim:

A hat formed of a single strip of braided 100 material, the braid consisting of two flat textile strands, each folded zigzag from end to end, one of said strands being laid upon the other and having its angularly disposed straight portions crossing the straight portions of the other strand, relatively narrow strands interwoven with the two first mentioned strands in such manner as to form a plait or braid, said plait or braid being 105 wound spirally to form a crown and a brim, the abutting edges of the braid or plait being united by a cord woven alternately through the folds thereof throughout its entire length.

GERALD H. SIMON.
